UNITED STATES PATENT OFFICE.

WILLIAM H. BOT, JR., OF GHENT, MINNESOTA.

BOILER-FLUE FASTENING.

No. 859,733.

Specification of Letters Patent.

Patented July 9, 1907.

Application filed May 21, 1906. Serial No. 317,970.

To all whom it may concern:

Be it known that I, WILLIAM H. BOT, Jr., a citizen of the United States, and a resident of Ghent, in the county of Lyon and State of Minnesota, have invented 5 a new and Improved Boiler-Flue Fastening, of which the following is a full, clear, and exact description.

This invention relates to improvements in means for securing flues in flue sheets of boilers, the object 10 being to provide a simple device by means of which a flue may be tightly clamped to the flue sheet, obviating the usual practice of expanding the flue.

I will describe a boiler flue fastening embodying my invention and then point out the novel features in 15 the appended claims.

Reference is to be had to the accompanying drawings forming a part of this specification, in which similar characters of reference indicate corresponding parts in all the figures.

20 Figure 1 is a sectional view of a flue and flue sheet showing a fastening embodying my invention; and Fig. 2 illustrates a clamping ring employed.

Referring to the drawings, 1 designates a flue, and 25 2 the flue sheet through which the flue passes; the flue sheet at its outer side is recessed to form an annular shoulder 3 with which the outer edge of a clamping ring 4 engages, the inner edge thereof engaging with the flue; the ring 4 is made of yielding metal so that it may be tightly clamped against the flue and 30 the said ring is conical as clearly indicated in Fig. 1.

Surrounding the outer end of the flue is a collar 5 having an annular flange 6 for engaging with the ring 4 and the said collar is provided with perforations to receive the clamping bolts 7, the heads of which are 35 to engage in the under-cut portions of blocks 8 attached to the flue sheet, as here shown.

The operation of the device is quite obvious from the drawings; that is, after placing a flue in position the clamping ring is passed over the same and into the 40 recess in the flue sheet, then the collar is placed in position and pressed toward the flue sheet by means of the nuts 10 on the bolts 7.

It will be noted that with my invention, a flue may be quickly secured in position, and as readily removed

when necessary. The expanding of the ring 4 will 45 form a tight joint, so as to prevent any possible leakage of water.

Having thus described my invention I claim as new and desire to secure by Letters Patent:—

1. In a boiler fastening, the combination with a flue sheet having an annular recess encircling the flue opening, the outer edge of said recess forming a shoulder and a flue extending through the flue opening, of a conical ring within the recess, the outer edge of the ring engaging the shoulder, and the inner edge engaging the flue, a collar 50 encircling the end of the flue and resting against the conical ring, blocks having undercut openings secured to the flue sheet on opposite sides of the flue opening, bolts engaging the undercut openings and traversing the openings in the collar, and nuts engaging the bolts whereby to 55 force the collar against the conical ring.

2. In a boiler flue fastening, the combination with a flue sheet having an annular shoulder around the flue opening, a flue extended through the opening of the sheet, a collar having a flange portion, a conical ring engaging 60 with said annular wall and also engaging with the flue, undercut blocks secured to the flue sheet, and bolts extended from said blocks through said collar.

3. In a boiler fastening, the combination with a flue sheet having an annular recess encircling the flue opening, the outer edge of said recess forming a shoulder, and a flue extending through the flue opening, of a conical ring within the recess, the outer edge of the ring engaging the shoulder, and the inner edge engaging the flue, a collar 70 encircling the end of the flue and resting against the conical ring and means detachably connected with the collar and with the flue sheet for forcing said parts towards each other whereby to force the ring into close contact with the flue and with the shoulder.

4. In a boiler fastening the combination with a flue sheet having an annular recess encircling the flue opening, the outer edge of said recess forming a shoulder and the flue extending through the flue opening, of blocks having undercut openings detachably connected with the flue sheet on opposite sides of the flue opening, a collar 75 encircling the end of the flue, bolts having their heads in the undercut openings and traversing the collar, nuts engaging the bolts whereby to force the collar toward the flue sheet, and a packing within the annular recess and 80 engaged by the collar.

In testimony whereof I have signed my name to this specification in the presence of two subscribing witnesses.

WILLIAM H. BOT, JR.
